UNITED STATES PATENT OFFICE.

ISOM P. HAWORTH, OF LOS ANGELES, CALIFORNIA.

FOLDABLE IRONING-BOARD.

1,135,895.

Specification of Letters Patent. Patented Apr. 13, 1915.

Application filed October 19, 1914. Serial No. 867,364.

To all whom it may concern:

Be it known that I, ISOM P. HAWORTH, a citizen of the United States, residing at Los Angeles, in the county of Los Angeles, State of California, have invented new and useful Improvements in Foldable Ironing-Boards, of which the following is a specification.

This invention relates to an ironing board which is adapted to be folded into a cabinet.

It is the object of this invention to provide an ironing board which can be swung in and out of a wall recess or cabinet, and to provide means whereby the board may be supported at different levels.

Another object is to provide means for counterweighting or balancing the board whereby the disposing of the board in either its open or folded position is facilitated.

Another object is to provide a combined ironing board and cabinet in which the ironing board can be folded into a compact space when not in use, and the cabinet utilized for the reception of the ironing appurtenances.

The invention is illustrated in the accompanying drawings, in which:

Figure 1 is a perspective view showing the ironing board in its operative position. Fig. 2 is a vertical section of the cabinet showing the ironing board in its folded position.

Fig. 3 is a detail section and elevation illustrating the ironing board as positioned on its higher level. Fig. 4 is a similar view showing the ironing board as disposed on its lower level.

More specifically, 5 indicates a cabinet formed with L-shaped side panels 6 and 7 connected together by a top panel 8 at their upper ends and by spaced back panels 9 and 10 on the rear edges thereof. The front of the cabinet 5 is formed with a casing 11 on the upper portion thereof which is fitted with an outwardly swinging door 12.

Slidably mounted in suitable guides between the back panels 9 and 10 to reciprocate vertically therebetween is a panel 14 to the lower edge of which an ironing board 15 is hinged to swing outwardly by means of hinges 16; this panel 14 being counterweighted by means of ordinary sash weights 17 and 18 connected to cords 19 and 20 passing over pulleys 21 and 22 mounted in the side panels 6 and 7. The cords 19 and 20 connect with the side edges of the panel 14 and the weights thereon are incased in housings 23 mounted on the outer faces of the side panels 6 and 7. The weights 17 and 18

are of such character as to not quite balance the panel 14 and the ironing board 15 so that when the ironing board 15 is in its vertical position against the inner face of the panel 9 as shown in Fig. 2 the panel 14 will be in its lowermost position and supported upon the upper edge of the panel 10; the upper edge of the panel 10 forming an abutment to limit the downward movement of the panel 14.

The lower edges of the casing 11 on the opposite sides of the door 12 terminate on a plane with the lower edge of the latter. Hingedly connected to the upper outer edges of the lowermost portion of the L-shaped side panels 6 and 7 by means of a hinge 24 is a panel 25 having inwardly extending side panels 26 and 27 thereon which are adapted to abut against the outer faces of the side panels 6 and 7 when the panel 25 is in its vertical position. Mounted on the upper end of the panel 25 and extending beyond the side panels 26 and 27 is a shelf 28 which is adapted to extend beneath the lower ends of the casing 11 and the door 12 when the panel 25 is in its uppermost position as shown in Fig. 2.

Hinged at 29 to the outer face of the panel 25 adjacent the upper end thereof is a panel 30 having supporting legs 31 formed thereon adapted to seat on the floor to form a support for the panel 25 to maintain the latter in an approximately horizontal position, as shown in Fig. 1. Pivottally mounted at 32 on the rear face of the panel 25 is a U-shaped frame 33, the connecting portion 34 of which is adapted to be arranged beneath the ironing board 15 to form a support for the latter when in its open and operative position.

The member 34 is formed with sockets 35 to receive pins 36 carried on a filler block 37 adapted to support the ironing board 15 and maintain it in its uppermost level, and which when removed from the member 34 is designed to be disposed on the upper edge of the panel 14 which is fitted with sockets 38 to receive the pins 36 on the block 37; the block 37 then forming an extension of the panel 14 to abut against the lower edge of the panel 9 and limit the upward movement of the inner end of the ironing board 15.

In the operation of the invention, assume the parts to be disposed in the position shown in Fig. 2 with the ironing board folded in a vertical position against the panel 9 and with the panel 14 supported on

the panel 10. To dispose the ironing board 15 in its operative position the panel 25 is rocked outwardly thus causing the panel 30 with the supporting legs 31 thereon to gravitate to the vertical position shown in Fig. 1. The door 12 is then opened, whereupon the U-shaped member 33 is turned on its hinge 32 into the vertical position shown in Fig. 1. The ironing board 15 is then rocked outwardly on its hinges 16 and when its weight is supported on the filler block 37 carried on the member 34 the weights 17 and 18 will operate to elevate the panel 14 and the inner end of the ironing board 15 until the upper 15 edge of the panel 14 abuts against the lower edge of the panel 9 which forms a stop to limit the upward movement of the panel 14. The ironing board 15 will then be supported in a horizontal position on its uppermost 20 level as particularly shown in Fig. 3. When it is desired to lower the ironing board 15 the filler block 37 is transposed from the member 34 to the upper edge of the panel 14 as particularly shown in Fig. 4; the filler block 25 37 then acting to dispose the inner end of the ironing board 15 on a lower plane; the outer end of the ironing board being disposed on a corresponding plane by reason of being supported on the member 34. The 30 lower portion of the cabinet is provided with a shelf 39 and is fitted with a hinged closure 40 beneath the hinged panel 25 to give access to the interior of the cabinet at this point, thus forming a space for the reception of 35 the implements and appurtenances employed in ironing.

What I claim is:

1. In a folding ironing board, the combination of a cabinet, a reciprocal panel thereon normally disposed in its lowermost position, counterweights connected to said panel, an ironing board hinged to said panel to

swing downwardly to a horizontal position, a stop for limiting the upward movement of the panel, and means engageable with the ironing board remote from the stop coöperating with said stop, whereby the board may be maintained in a horizontal position. 45

2. A folding ironing board, comprising a cabinet, a vertically reciprocal panel therein, a counterweight attached to said panel, a stop for limiting the upward movement of the panel, an ironing board hinged to said panel to swing in and out of the cabinet, a hinged panel on said cabinet beneath the ironing board, and means on said panel adapted to engage the ironing board when said panel is in its horizontal position engageable with the ironing board coöperating with the stop to support the ironing board 60 in its horizontal position. 50

3. A folding ironing board, comprising a cabinet, a vertically reciprocal panel therein, a counterweight attached to said panel, a stop for limiting the upward movement of the panel, an ironing board hinged to said panel to swing in and out of the cabinet, a hinged panel on said cabinet beneath the ironing board, means for supporting said hinged panel in a horizontal position, a member on said panel adapted to engage the ironing board and coöperate with the stop to support the ironing board in a horizontal position, and a filler block adapted to be interchangeably mounted on said member and said reciprocal panel, whereby the ironing board may be adjusted at different levels. 65 70 75

In witness that I claim the foregoing I have hereunto subscribed my name this 1st day of October, 1914.

ISOM P. HAWORTH.
